PHOTOTHERAPY LAMP

Howard S. Haft, Chicago, Ill., assignor to
Art Specialty Company

Filed June 24, 1970, Ser. No. 23,638

Term of patent 14 years

Int. Cl. D26—99
U.S. Cl. D48—20

Fig. 1

Fig. 2

FIG. 1 is a perspective view of a phototherapy lamp embodying my new design, the opposite side having the same appearance;

FIG. 2 is a second perspective view showing the lamp in an alternate position.

I claim:

The ornamental design for a phototherapy lamp, as shown and described.
